UNITED STATES PATENT OFFICE.

HAROLD H. WHEELER AND HERBERT J. NILSON, OF LORAIN, NORTH DAKOTA.

GRAIN-DOOR.

1,355,874.

Specification of Letters Patent. Patented Oct. 19, 1920.

Application filed March 22, 1920. Serial No. 367,597.

To all whom it may concern:

Be it known that we, HAROLD H. WHEELER and HERBERT J. NILSON, citizens of the United States, residing at Lorain, in the 5 county of Renville and State of North Dakota, have invented certain new and useful Improvements in Grain-Doors; and we do hereby declare the following to be a full, clear, and exact description of the invention, such as will enable others skilled in 10 the art to which it appertains to make and use the same.

Our invention has for its object to provide an extremely simple and highly efficient grain door for cars, and to this end, 15 it consists of the novel devices and combinations of devices hereinafter described and defined in the claims.

In the accompanying drawings, which 20 illustrate the invention, like characters indicate like parts throughout the several views.

Referring to the drawings:

Figure 1 is a fragmentary perspective view of a box car body having our improved 25 grain door installed therein, looking at the same from the inside of said body and with the grain door closed;

Fig. 2 is a view corresponding to Fig. 1, with the exception that the outer door section has been partly opened to produce 30 between the door sections a relief port;

Fig. 3 is a transverse vertical section taken on the line 3—3 of Fig. 1, on an enlarged scale;

Fig. 4 is an elevational view in part section showing the track bar and gear; and

Fig. 5 is a detail view in transverse section taken on the line 5—5 of Fig. 4.

The numeral 6 indicates an ordinary box 40 car body having in its sides the usual door openings formed between door posts 7 and provided with sliding outside doors 8. Secured to the inside of the car body 6, at each side of the door opening, is a sheath 9 preferably formed from sheet metal and entirely closed except for a door opening and a grain escape passageway 10 at the bottom thereof. These sheaths 9 are shallow and take up very little room in the car body. At the door opening in each sheath 9 is a supplemental door post 11, which bears against the inner face of said sheath and is secured to the floor and top of the car body 6.

The improved grain door comprises inner 55 and outer sections 12 and 13, respectively, mounted for reverse sliding movement in

the sheaths 9. These door sections 12 and 13 are preferably formed from sheet metal and may be slid completely into the sheaths 9 so that they are entirely out of the way, 60 or slid part way out of said sheaths into overlapping arrangement to close the door opening. When the door sections 12 and 13 are closed, they overlap both door posts 7 to securely hold said sections against outward pressure. To further assist in holding the door sections against outward pressure, there is secured to the floor of the car body 6, outward of the door sections, a cleat 14. The overlapping vertical edges of the 70 door sections 12 and 13 are oblique in respect to each other, and preferably, as shown, said overlapping edges are both beveled downwardly and backwardly to produce therebetween, when the outer door section is opened, a relief port 15 that progressively increases in size as said door section is opened.

A horizontal reinforcing bar 16 is secured to the inner door section substantially at 80 the vertical center thereof and has a length substantially equal to the width of said door section so as to overlap the door posts 7 when said door section is closed. The end of the reinforcing bar 16, which projects 85 beyond the oblique edge of the inner door section 12, has formed thereon a hook 17 arranged to interlock with a pin or lock lug 18 on one of the supplemental door posts 11 and thereby hold said inner door 90 section closed. On the top edge of the outer door section 13, is an inwardly projecting track bar 19 which rests upon the top edge of the inner door section 12 and slidably supports said outer door section thereon. 95 By reference to Fig. 5, it will be noted that the top edge of the inner door section 12 is also bent slightly inward to afford a reinforcing flange.

On the inner edge of the track bar 19, 100 is a downturned flange 20, which overlaps the flanged upper edge of the inner door section 12 and thereby locks the two door sections together at their top edges against lateral movement in respect to each other. 105 The flanged track bar 19 also guides the two door sections for parallel sliding movement. The track bar 19 is of such length as to overlap the door posts 7 when the outer door section 13 is closed and thereby materially 110 reinforces and holds the door sections against outward pressure.

Formed on the top of the track bar 19 are longitudinally spaced gear teeth 21, which mesh with a pinion 22 journaled in one of the sheaths 9. The pinion 22 may be rotated to impart endwise sliding movement to the outer door section 12 by means of a hand wheel 23 secured to the inner end of the shaft of said pinion. In some instances, it might be desirable to provide the shaft of 10 the pinion with means for operating said pinion from the outside of the car body. To hold the outer door section 13 closed, there is pivoted at one of the door posts 7 a lock finger 24 arranged to rest on the track 15 bar 19 under the action of gravity between certain of the gear teeth 21.

If desired, anti-friction devices may be provided for the inner door section to cause the same to slide more easily, and, likewise, 20 anti-friction devices may be interposed between the track bar 19 and the top of the inner door section 12 to cause the outer door section 13 to slide more easily.

To unload grain from a car having our 25 improved grain door installed therein, it is only necessary to slightly open the outside door section 13 by manipulating the hand wheel 23 and thereby produce between the door sections 12 and 13 a relatively small 30 grain release port 15. As the pressure of the grain is relieved from the door, the wheel 23 can be operated from time to time to increase the size of the escape port 15, and finally the outer door section may be moved 35 into a complete open position. The operator may then get into the car, if necessary, and open the inner door section 12 to complete the unloading of the car.

From the above description, it is evident 40 that our improved grain door may be installed in a car body without cutting or otherwise mutilating the same, and it does not, in any way, interfere with the customary outside doors, or the use of wooden 45 doors if it is desired to use the same when loading cars with coal or other bulk commodities.

What we claim is:—

1. The combination with a car body having 50 a side door opening, of a grain door for the door opening comprising two sections mounted on opposite sides of the door opening for sliding movement into overlapping arrangement to close the door opening, the overlapping vertical edges of the door sections being in oblique relation to each other to produce therebetween a relief port when one of the door sections is opened and which relief port progressively increases in size 55 as said door section is opened.

2. The combination with a car body having 60 a side door opening, of a grain door for the door opening comprising two sections mounted on opposite sides of the door opening for sliding movement into overlapping 65

arrangement to close the door opening, the overlapping vertical edges of the door sections being beveled backwardly and downwardly from their top edges to produce therebetween a relief port when one of the 70 door sections is opened and which relief port progressively increases in size as said door section is opened.

3. The combination with a car body having 75 a side door opening, of a grain door for the door opening comprising two sections mounted on opposite sides of the door opening for sliding movement into overlapping arrangement to close the door opening, the overlapping vertical edges of the door sections being in oblique relation to each other to produce therebetween a relief port when one of the door sections is opened and which relief port progressively increases in size 80 as said door section is opened, 85 said door sections being of such length at their tops as to overlap the car body at the door opening when closed.

4. The combination with a car body having 90 a side door opening, of a grain door for the door opening comprising inner and outer sections mounted on opposite sides of the door opening for sliding movement into overlapping arrangement to close the door opening, the overlapping vertical edges of the door sections being in oblique relation to each other to produce therebetween a relief port when one of the door sections is opened and which relief port progressively increases in size 95 as said door section is opened, said inner door section being provided with a reinforcing bar of such length as to overlap the car body at the door opening when said inner door section is closed.

5. The combination with a car body having 105 a side door opening, of a grain door for the door opening comprising inner and outer sections mounted on opposite sides of the door opening for sliding movement into overlapping arrangement to close the door opening, the overlapping vertical edges of the door sections being in oblique relation to each other to produce therebetween a relief port when one of the door sections is opened and which relief port progressively increases in size 110 as said door section is opened, said inner door section being provided with a reinforcing bar of such length as to overlap the car body at the door opening when said inner door section is closed, 115 and lock elements on the reinforcing bar and a part secured to the car body for holding the inner door section closed.

6. The combination with a car body having 120 a side door opening, of a grain door for the door opening comprising inner and outer sections mounted on opposite sides of the door opening for sliding movement into overlapping arrangement to close the door opening, the overlapping vertical edges of 125 130

the door sections being in oblique relation to each other to produce therebetween a relief port when one of the door sections is opened and which relief port progressively increases in size as said door section is opened, said inner door section being provided with a reinforcing bar of such length as to overlap the car body at the door opening when said inner door section is closed, 5 said outer door section being slidably supported on the inner door section.

7. The combination with a car body having a side door opening, of a grain door for the door opening comprising inner and outer sections mounted on opposite sides of the door opening for sliding movement into overlapping arrangement to close the door opening, the overlapping vertical edges of the door sections being in oblique relation 10 to each other to produce therebetween a relief port when one of the door sections is opened and which relief port progressively increases in size as said door section is opened, said inner door section being provided with a reinforcing bar of such length as to overlap the car body at the door opening when said inner door section is closed, said outer door section having on its top edge a track bar mounted on the 15 inner door section and slidably supporting said outer door section therefrom and lock the door sections together against lateral movement at their top edges.

8. The combination with a car body having a side door opening, of a grain door for the door opening comprising inner and outer sections mounted on opposite sides of the door opening for sliding movement into overlapping arrangement to close the door opening, the overlapping vertical edges of the door sections being in oblique relation to each other to produce therebetween a relief port when one of the door sections is opened and which relief port progressively increases 20 in size as said door section is opened, said inner door section being provided with a reinforcing bar of such length as to overlap the car body at the door opening when said inner door section is closed, said outer door section having on its top edge a tooth-equipped track bar mounted on the inner door section and slidably supporting said outer door section therefrom and lock the door sections together against lateral movement at their top edges, a pinion journaled on the car body and meshing with the teeth on the track bar, and means for operating the pinion to impart sliding movement to the outer door section.

60 9. The combination with a car body having a side door opening, of a grain door for the door opening comprising inner and

outer sections mounted on opposite sides of the door opening for sliding movement into overlapping arrangement to close the door opening, the overlapping vertical edges of the door sections being in oblique relation to each other to produce therebetween a relief port when one of the door sections is opened and which relief port progressively increases in size as said door section is opened, said inner door section being provided with a reinforcing bar of such length as to overlap the car body at the door opening when said inner door section is closed, said outer door section having on its top edge a tooth-equipped track bar mounted on the inner door section and slidably supporting said outer door section therefrom and lock the door sections together against lateral movement at their top edges, a pinion journaled on the car body and meshing with the teeth on the track bar, means for operating the pinion to impart sliding movement to the outer door section, and a lock on the car body arranged to be moved into a position to be engaged by the teeth of the track member to hold the outer door section closed.

10. The combination with a car body having a side door opening, of a sheath secured to the car body at each side of the door opening, a grain door for the door opening comprising two sections mounted in said sheaths for sliding movement into overlapping arrangement to close the door opening, the overlapping vertical edges of the door sections being in oblique relation to each other to produce therebetween a relief port when one of the door sections is opened and which relief port progressively increases 90 in size as said door section is opened.

11. The combination with a car body having a side door opening, of a sheath secured to the car body at each side of the door opening, a grain door for the door opening comprising two sections mounted in said sheaths for sliding movement into overlapping arrangement to close the door opening, the overlapping vertical edges of the door sections being in oblique relation to each other to produce therebetween a relief port when one of the door sections is opened and which relief port progressively increases 95 in size as said door section is opened, each of said sheaths being provided with a grain escape passageway.

In testimony whereof we affix our signatures in presence of two witnesses.
